RADIATOR

Harry Del Mar, New York, N. Y.

Application August 15, 1931. Serial No. 557,247

7 Claims. (Cl. 257—141.)

My invention relates to a radiator for house heating purposes and more particularly to a vertically disposed tube or jacket having an air flue which radiator is adapted to be placed in 5 the corner of a room, where it will not take up useful floor space.

This invention is a continuation in part of the radiator illustrated and described in my co-pending application serial No. 360,162, which has now 10 matured into Patent No. 1,838,083, issued Dec. 29, 1931.

The principal object is to construct a vertical tubular radiator which will conveniently fit into 15 the corner of a room, and provide same with air flues through which air will be drawn in from below at room temperature and discharged from above at a higher temperature.

Many advantages are obtained from a radiator 20 of this type among them being the economy of space, increased radiation, and improved circulation due to the long air flues which create a turbulent suction and discharge due to their length. The layer of warm air at the upper portion 25 of a room is activated by the rapid discharge of air, thereby providing circulation which is not obtainable with the present type of low radiator installations.

Other features will appear in the following 30 specification and drawing in which a preferred embodiment of my invention is described and illustrated.

In the drawing:

Fig. 1 is an elevational view of one form of 35 radiator.

Fig. 2 is an enlarged vertical section through the radiator shown in Fig. 1.

Fig. 3 is a cross section taken on the lines 3—3 40 of Fig. 2.

Fig. 4 is a vertical section through a radiator showing another form of radiator structure.

Fig. 5 is a cross section on the line 5—5 of 45 Fig. 4.

Fig. 6 is a vertical section of a radiator with a feed line passing through the air flue.

Fig. 7 is a fragmentary vertical section through a radiator having a plurality of flue tubes inserted therein.

Fig. 8 is a cross section taken on the lines 8—8 50 of Fig. 7.

Fig. 9 is an elevational view of a triangular form of radiator with part broken away and

Fig. 10 is a cross section taken on the line 10—10 of Fig. 9.

Referring to Figs. 1, 2 and 3, the body of the radiator, designated generally by the reference

character 10, comprises a contiguous outer wall 12 and inner wall 14, which form a tubular jacket, having a chamber 16 between said walls, through which steam or hot water will be passed, according to the heating system desired. The 60 body is preferably shaped into a jacket formation to provide a central air flue 18, through which air is adapted to be drawn from below at room temperature, become heated by the radiated heat from the inner wall 14, during its upward passage through said flue, and be discharged through the upper outlet at a higher temperature. To increase the radiating surface, the outer jacket walls 12 are corrugated as indicated at 20, throughout their entire length, and 65 if desired the inner walls 14 may also be corrugated as indicated at 22 Figs. 4 and 5.

Suitable inlet and outlet openings are preferably provided at the top and bottom of each radiator body as at 24—26, and each opening is 70 provided with the usual fittings for making the necessary connections. Reinforcing bands 27 may be secured to the outer wall of the radiator body as shown in Fig. 1, to strengthen the wall and provide resistance against internal pressure. 80 While I prefer to construct each radiator of substantially the full room height, allowing sufficient end space above and below for the intake and discharge of air through the flues, it may be desirable for some purposes to construct shorter 85 sections and join them together as shown in broken lines in Fig. 2. A suitable base 29 is provided to support the radiators on each floor.

In Fig. 6, I have shown a radiator with the feed line 30 passing through the air flue 18a. 90 Instead of stopping the feed line 30 at the lower T connection as in Fig. 1, the feed pipe is continued through the air flue and provides additional radiated heat to the air passing through said flue. A branch connection is taken off the feed line at 32 to one opening in the bottom of the radiator and a valve 34 is placed in said branch to control the supply to the radiator. This form of structure is preferred when used in buildings having more than one floor, since 100 the feed line will run through all the floors and any number of branch connections may be taken off. The use of the radiator without the feed line running through, is particularly adapted for bungalows, garages, top floors and similar places. 105

Additional flues 30 may be provided as shown in Figs. 7 and 8 by inserting tubes 38 within the chamber 16a and securing same at their ends to the top and bottom of the radiator by welding or any other suitable way.

The heat from the flue may also be utilized to advantage for heating small rooms in the floor above by placing one end of an apron 40 around the upper end of the radiator and having the 5 opposite end pass through the upper floor as indicated in dot and dash lines in Fig. 1. A register 42 may be added to control the heat, in the manner usually provided in hot air installations.

10 Still another adaptation of my improved radiator is illustrated in Figs. 9 and 10, which shows a radiator having two sides 44-46 at substantially right angles to each other, which are adapted to fit in close relation to the walls in the 15 corner of a room. A third side 48 completes the outer wall, all three of said sides being formed contiguously with an inner wall 50, to complete the jacket formation and provide for a flue 52. By placing angle straps 54 at the edges of this 20 structure as indicated in Fig. 10, the walls 44 and 46 are supported in spaced relation to the building wall 56, thereby providing an additional flue 58. While the structure shown is substantially triangular, it is to be understood that other 25 shapes such as square or rectangular may be made if desired.

Various other forms of structure may be made which will come within the scope of the following claims.

30 I claim:

1. A radiator of the character described comprising in combination, an elongated vertically disposed substantially cylindrical jacket, said jacket comprising a corrugated outer wall and 35 cylindrical inner wall, the interior of which forms a steam or water tight compartment, in-

let and outlet connections at the ends of said jacket, and an air flue formed by the inner exposed wall of said jacket, through which air is adapted to be drawn from below at room temperature and discharged from above at a higher 80 temperature.

2. A combination as defined in claim 1 in which a feed line is adapted to pass through the air flue, from which feed line a connection is taken to said radiator. 85

3. The combination of a vertically disposed steam or hot water jacket having an air flue therethrough, with an apron, one end of which is adapted to be secured to the upper end of said jacket and the other end pass through a 90 floor section opening into the room above.

4. A radiator of the character described comprising in combination, a vertically disposed jacket having inlet and outlet connections, a flue formed by the inner wall of said jacket, and a 95 feed line passing through said flue.

5. In a radiator, the combination of a vertically disposed jacket having a substantially triangular cross section, two walls of which form substantially a right angle and are adapted to conveniently fit into the corner of a room, and an air 100 flue formed by the inner wall of said jacket.

6. A combination as defined in claim 5, in which a feed line passes through the air flue. 105

7. In an elongated vertical radiator, comprising 110 interconnected sections placed one above the other, each section comprising a tubular jacket, with a flue formed by the inner wall of said jackets, and a feed line passing through said flue.
